UNITED STATES PATENT OFFICE

JOSEPH L. WEBER, OF GREEN BAY, WISCONSIN, ASSIGNOR TO WEBER-McDONALD WALL TIE COMPANY, A CORPORATION OF WISCONSIN

FORM TIE FOR CONCRETE STRUCTURES

Application filed October 8, 1928. Serial No. 310,987.

The invention relates to form ties for concrete structures, and more especially to a method and means for retaining construction forms for concrete or the like.

The primary object of the invention is the provision of means of this character, wherein the ordinary or customary sections of molds composed of planks or boards arranged edge-wise in abutting vertical relation, for the erection of a wall, curbing, siding or foundation, can be temporarily connected at opposite sides of the mold, so that on the hardening of the structure, the sections can be conveniently released, without damage to the mold and also without excessive exertion on the part of mechanic, thereby enabling the dismantling of the mold with dispatch.

Another object of the invention is the provision of means of this character, wherein the construction thereof is novel in form, requiring like fasteners for all ties used in connection with the mold or form, these fasteners being easily accessible, so as to permit quick and convenient removal of the sections of the mold or form, when the structure has become set.

A further object of the invention is the provision of means of this character, which is extremely simple in construction, thoroughly reliable and efficient in purpose, strong, durable, readily and easily applied and removed from a form or mold, standard in character, and inexpensive to manufacture.

With the above and other objects in view the invention consists in the features of construction, combination and arrangement of parts as will be hereinafter more fully described, illustrated in the accompanying drawings, showing the preferred embodiments of the invention, and pointed out in the claim hereunto appended.

In the accompanying drawings:

Figure 1, is a fragmentary plan view of a pair of form sides between which a concrete wall is to be formed, showing one form of a tie constructed in accordance with the invention applied.

Figure 2, is a vertical cross section taken approximately on the line 2—2 of Figure 1.

Figure 3, is a view similar to Figure 1,

showing a slight modification of the invention.

Figure 4, is a vertical cross section taken approximately on the line 4—4 of Figure 3.

Figure 5, is a view similar to Figure 1, showing a further slight modification of the invention.

Figure 6, is a vertical cross section taken approximately on the line 6—6 of Figure 5.

Figure 7, is a side view of the tie shown in Figure 1.

Figure 8, is an end view thereof.

Figure 9, is a side view of the tie shown in Figure 3.

Figure 10, is an edge view thereof.

Figure 11, is a side view of the tie shown in Figure 5.

Figure 12, is a edge view thereof.

Figures 13, 14, 15, and 16, are detail views of a still further modification of the invention.

Similar reference characters indicate corresponding parts throughout the several views in the drawings.

Referring to the drawings in detail, the form or mold within which the concrete walls or the like are to be molded is comprised generally of two sides A, and B, respectively, formed by boards or the like tied together with spacing members C, located at intervals, which spacing members are under compression when the forms or molds are drawn together by the ties herein after fully described.

With reference to Figures 1, 2, 7, and 8, of the drawings, the tie therein shown comprises a pair of bails, each including a straight run of wire 10, having the required length and rigidity, formed at one end portion with a right angular terminal 11, provided with an eye 12, while the other end portion is formed with an outwardly distorted terminal 13, provided with an eye extremity 14. These bails are reversely applied about the spacing members C, and between the meeting edges of the boards of the sides A, and B, as is clearly shown in Figures 1, and 2, of the drawings.

The distorted terminal 13, of each wire serves to overlap the terminal 11, adjacent thereto of the other wire for snug relationship, and passed through said eyes 12, and 14, 100

are nails 15, which are driven into the spacing members C, as shown.

In Figures 3, 4, 9 and 10, of the drawings there is shown a slight modification of tie, wherein each bail includes an intermediate angular portion 16, and outer non-aligned straight portions 17, one of the latter being formed with a hook terminal 18, provided with an eye extremity 19, and the other with a right angular terminal 20, having an eye extremity 21. These bails are reversely applied to the form or mold, so that the hook terminals 18, embrace partially the spacing members C, and the right angular terminals 20, overlap the outer edge portions of said members, as clearly shown in Figures 3, and 4, of the drawings. Engaged in the eye extremities 19, and 21, are nails 22, these being driven into the spacing members C.

With reference to Figures 5, 6, 11, and 12, of the drawings, there is shown a further modification of tie, wherein the hook terminals 23, and 24, are reversely set, and formed with eye extremities 25, the latter receiving nails 26, which are driven into the spacing members C, when the bails are applied as shown in Figures 5, and 6, of said drawings.

It should be apparent that when the form or mold including the sides A, and B, and the spacing members C, are confined within a trench beneath the ground surface, the ties can be readily released by removal of the nails from the eyes, and such nails are readily accessible to an extractor operated at the ground surface.

With reference to Figures 13, 14, 15 and 16, of the drawings there is shown a still further modification of the invention, wherein each bail, there being two as companions, comprises a straight run 27, having right angular terminals 28, one being formed with an eye extremity 29, while the other is formed with a hook bill 30. In the use of the bails, these are reversely disposed in the pair, so that the bill 30, of each will be inserted in the eye extremity 29, thus removably interlocking the pair together for embracing relation to the work similar to Figures 1, and 2, of the drawings.

What is claimed is:

A form tie of the kind described, comprising a pair of relatively stiff wire members, each including a long stretch and relative short bent terminals, the terminals being constructed to embrace a wall form, and eyes formed on the terminals and adapted to receive fasteners to be driven into the wall form to hold said terminals in embracing relation thereto, said eyes of the respective terminals being free of each other and non-twisted together, the long stretches of the members being adapted to lie crosswise of the wall form.

In testimony whereof I affix my signature.

JOSEPH L. WEBER.
